COMPRESSOR FOR REFRIGERATING APPARATUS

Robert N. Feicht, Dayton, Ohio, assignor to General Motors Corporation, Dayton, Ohio, a corporation of Delaware

Application February 26, 1938, Serial No. 192,846

1 Claim. (Cl. 230—47)

This invention relates to refrigerating apparatus and more particularly to an improved refrigerating system and multiple effect compressor capable of operating at an extremely high efficiency.

It is known that refrigerating systems operate at a higher efficiency when operating at a higher back pressure. The operation at a higher back pressure decreases the pressure differential which the compressor is required to overcome and the volume of evaporated refrigerant required to be compressed. However, in order to get low temperatures it is necessary that a low back pressure be carried. Heretofore this has been done by expanding the refrigerant from the condenser directly in a single stage into the evaporator where the refrigerant evaporates at the low back pressure and all the evaporated refrigerant must be returned to the condenser by the compressor which must overcome the relatively large pressure differential between the evaporator pressure and condenser pressure.

It is an object of my invention to reduce the pressure of the refrigerant passing from the condenser to the evaporator in stages and to withdraw the evaporated refrigerant at one or more intermediate stages and to use a compressor capable of taking full advantage of the added efficiency obtainable from this higher back pressure evaporated refrigerant in order to make the system more efficient.

It is another object of my invention to provide an improved multiple effect compressor capable of operating with great efficiency while drawing gas at two different back pressures.

It is another object of my invention to provide an improved multiple effect rotary compressor having a high volumetric efficiency.

It is still another object of my invention to provide a multiple effect rotary compressor which requires no check valves in the suction lines.

It is still another object of my invention to provide an improved multiple effect rotary compressor in which the impeller covers, uncovers and separates the suction ports so as to properly control the admission of gas through each of the ports in order to secure the highest efficiency without the use of any other valves.

It is another object of my invention to provide a modified form of multiple effect rotary compressor.

an improved multiple effect rotary compressor in which a means operated by the drive shaft is employed to control the admission of refrigerant through the suction ports of the compressor.

5 It is another object of my invention to provide an improved oiling system for rotary compressors in which the oil is elevated upon the inside of the drive shaft as well as the outside.

Further objects and advantages of the present invention will be apparent from the following description, reference being had to the accompanying drawings, wherein a preferred form of the present invention is clearly shown.

In the drawings:

15 Fig. 1 is a diagrammatic view of a refrigerating system embodying my invention;

Fig. 2 is a sectional view of the compressor shown in Fig. 1 taken along the line 2—2 of Fig. 5;

20 Fig. 3 is a sectional view of the compressor proper looking downwardly directly upon the cylinder block and impeller. The impeller is shown in a position to begin to open the high pressure suction inlet port to permit the admission of the high pressure gas into the compression chamber;

Fig. 4 is a view similar to Fig. 3 with the impeller located so as to show the end of the open period of the high pressure port;

25 Fig. 5 is a view similar to Figs. 3 and 4 showing the impeller in position to begin a new suction stroke;

Fig. 6 is a sectional view of the compressor proper taken along the lines 6—6 of Fig. 5;

30 Fig. 7 is a sectional view taken along the lines 7—7 of Fig. 4;

Fig. 8 is a sectional view taken along the lines 8—8 of Fig. 4;

Fig. 9 is a sectional view taken along the lines 9—9 of Fig. 5;

Fig. 10 is a sectional view taken along the lines 10—10 of Fig. 3;

Fig. 11 is a sectional view of a liquid and gas separator shown between the two restrictors in Fig. 1, taken along the lines 11—11 of Fig. 12;

Fig. 12 is a sectional view taken along the lines 12—12 of Fig. 11;

Fig. 13 is a horizontal sectional view of a modified form of multiple effect rotary compressor.

The impeller is shown in position to begin the compression stroke;

Fig. 14 is a view similar to Fig. 13 in which the impeller is at the point of beginning to open the high pressure suction port;

Fig. 15 is a view similar to Figs. 13 and 14 in which the impeller has fully opened the high pressure suction port;

Fig. 16 is a view similar to Figs. 13, 14 and 15 in which the impeller is at the point of closing the high pressure suction port;

Fig. 17 is a sectional view taken along the lines 17-17 of Fig. 15;

Fig. 18 is a sectional view of another modified form of multiple effect rotary compressor provided with a roller type impeller, the impeller being shown in position of uncovering the high pressure suction port;

Fig. 19 is a sectional view similar to Fig. 18 in which the impeller is shown closing the high pressure suction port;

Fig. 20 is a sectional view taken along the lines 20-20 of Fig. 18;

Fig. 21 is a horizontal sectional view of another modified form of multiple effect rotary compressor with a roller type impeller shown in position just after the beginning of the compression stroke with the impeller at the point of uncovering the high pressure suction port;

Fig. 22 is a horizontal sectional view similar to Fig. 21 with the impeller shown at the point of closing the high pressure suction port;

Fig. 23 is a horizontal sectional view similar to Figs. 21 and 22 in which the impeller is shown in position fully uncovering the high pressure suction port; and

Fig. 24 is a sectional view taken along the lines 24-24 of Fig. 23.

Briefly I have shown in Fig. 1 a refrigerating system comprising a multiple effect rotary compressor enclosed in a sealed unit which supplies compressed refrigerant to a condenser which in turn supplies liquid refrigerant to a restrictor embodied in the heat exchange device within which the pressure of the refrigerant is reduced, thereby permitting the evaporation of some of the refrigerant to cool the remainder of the liquid refrigerant. From this first restrictor the liquid and evaporated refrigerant passes into a separator from which the evaporated refrigerant is drawn through the high pressure suction conduit which passes in heat exchange relation with the first restrictor and conducts this high pressure evaporated refrigerant from the separator to the high pressure suction inlet of the compressor. The remainder of the liquid refrigerant passes from the bottom of the separator through a second restrictor embodied in the heat exchange device and connected to the evaporator. The evaporated refrigerant is withdrawn from the evaporator through a second suction line which passes in heat exchange relationship with the second restrictor and connects to the low pressure inlet of the multiple effect compressor.

In Figs. 2 to 10 inclusive are shown one form of a multiple effect compressor in which the roller is keyed to the eccentric shaft in order to form an impeller of the fixed eccentric type. A slot is cut into the impeller which is employed to register with the high pressure suction inlet port and a second part is provided leading to the compression chamber when the impeller has moved to position where it covers the low pressure inlet port located near the divider block. These ports remain registered for about a sixth of a revolution

during which time the impeller and the divider block always separate the high and low pressure ports so as to prevent any gas from the high pressure inlet port from being passed back into the low pressure inlet port.

In Figs. 13 to 17 a similar compressor is shown more or less diagrammatically in which the high pressure suction inlet port communicates directly with a port in the impeller which opens directly into the compression chamber.

In Figs. 18 to 20 the impeller is formed of a roller upon the eccentric and only a single high suction pressure port is employed in the casing of the compressor. This port is located so that it opens slightly before the low pressure suction inlet is covered and closes after compression is begun so that it is deemed advisable to provide each port with a check valve.

In Figs. 21 to 24 inclusive there is shown a compressor very similar to that shown in Figs. 18 to 20, including a roller impeller mounted upon an eccentric, but in this form a high pressure inlet port is located and so shaped that no check valves are necessary. In this form the low pressure inlet port is covered and the high pressure inlet port is uncovered and again covered before one-half of the compression stroke is completed.

Referring now more particularly to the drawings and particularly to Fig. 1, there is shown a multiple effect compressor 30 for compressing the refrigerant and for forwarding the compressed refrigerant to a condenser 32 where the compressed refrigerant is liquefied and forwarded to a restrictor 34 which contains an elongated orifice. The other end of the restrictor 34 is connected to a liquid and gas separator 36 which is better shown in Figs. 11 and 12. This separator includes a cylinder 38 plugged by a plug 40 at its upper end and a plug 42 at its lower end. Within the cylinder is a vertical pin 44 upon which are mounted baffles 46 which are separated by spacers 48. The restrictor tube 34 extends through the upper two baffle members. The baffle members are staggered so that the liquid will pass downwardly at a relatively slow rate over the various baffles to the bottom of the separator. In this separator the liquid has an ample opportunity to evaporate and this evaporation cools the remainder of the liquid down to a temperature corresponding to the pressure which may be kept within the separator.

This pressure within the separator is kept at a relatively low figure by a high pressure suction conduit 50 which extends out of the upper plug 40 of the separator 36 into heat exchange relationship with the restrictor 34 in a heat exchange device 52 which is shown diagrammatically. The heat exchange device 52 is shown as a container containing a heat transfer liquid and having the restrictor tube 34 and the high pressure suction tube 50 traversing from top to bottom. However, any other suitable form of direct or indirect heat exchange device may be employed. Preferably the heat exchange between these two tubes should be arranged in the best counterflow fashion in order to obtain the greatest efficiency from the use of this arrangement for pre-cooling the liquid refrigerant and removing the flash gas by connecting the separator 36 intermediate the two restrictor portions to the high pressure suction inlet of a multiple effect compressor.

The liquid in the separator collects at the bottom thereof and is withdrawn through a second restrictor tube 54 which extends to the evaporator inlet located at the bottom of the evaporator

56. The refrigerant evaporates within the evaporator under reduced pressure and leaves through a low pressure suction conduit 58 which extends into heat exchange relationship with the restrictor tube 54 in the heat exchange means 60, which may be of any suitable direct or indirect type, preferably one which is arranged in counter-flow fashion. This low pressure suction conduit after leaving the heat exchange device 60 passes through insulating means 62 which also surrounds the separator 36 and the lower portion of the heat exchange device 52. The heat exchange device 60 as well as the evaporating means 56, is exposed to the medium to be cooled found within the enclosure 64 indicated diagrammatically. The low pressure suction conduit is insulated all the way to the low pressure inlet of the sealed motor-compressor unit 30. The operation of the motor compressor unit 30 is controlled by a snap acting pressure-operated switch means 66 provided with a thermostat bulb 68 located in heat exchange relationship with the evaporating means 56.

By employing this system with the separator between the two restrictors and by employing a multiple effect compressor with a high pressure inlet port connected to withdraw evaporated refrigerant from the separator, the refrigerant used for cooling the liquid supply to the evaporating means is removed at a relatively high back pressure so that a saving in efficiency of as much as 25% can be had. This saving in efficiency varies, of course, with the refrigerant used. The saving is further increased by the use of the dual heat exchange shown.

Motor-compressor unit

Referring now more particularly to Figs. 2 to 10 for a showing of the motor-compressor unit 30, there is shown in Fig. 2 an upper inverted cup-shaped housing member 70 provided with a flange 72 at its lower end which is welded to a similarly out-turned flange 74 of a bottom basin-shaped housing member 76. Pressed into the upper housing member 70 is a cup-shaped motor frame member 78 having a rim portion 80 which fits into the housing member 70, a central bearing portion 84 containing a lower bearing 86 and an upper bearing 88, and a web portion 82 which connects the rim portion 80 with the central bearing portion.

The rim portion 80 of the frame member 78 carries the stator 90 of an electric motor, preferably of the split phase or capacitor start induction motor, which has a rotor 92 mounted upon a thimble member 94 which surrounds the bearing 88 and is pressed onto the upper end of the eccentric shaft 96 supported by the bearings 86 and 88. The shaft 96 serves as a motor shaft and also as the drive shaft for driving the compressor. At its lower end it is provided with an eccentric 98 which is keyed by the key 102 to a roller member 104 which in this case is not a true roller member because it is fixed to the eccentric and therefore in reality forms a part of a large eccentric member which includes the eccentric 98 as well as member 104. These two members rotate around within the cylinder wall 106 of the compressor. This cylinder wall is fastened by means of screws 108 and pins 110, to a lower finished surface of the metal web or flange surrounding the bearing 86. The screws 108 also serve to fasten the bottom plate 112 to the cylinder 106.

The bottom plate 112 is provided with a central aperture 114 covered by a screen 116. This

screen 116 is held in place by a muffler 118 which covers the remainder of the bottom of the compressor and receives the gas from the compressor outlet. The aperture 114 in the bottom plate 112 is located below the oil level within the sealed unit 30, and in order to lubricate the bearings 86 and 88 a pin 120 is set inside of a threaded aperture in the eccentric 98. The lower end of this pin is slotted and receives a cotter-pin 122 which is lodged within a slot provided in the bottom plate 112. The provision of the pin 120 within the threaded aperture in the eccentric 98 carries the oil upwardly until it reaches an outlet 124 which conducts the oil to the oil groove 126 provided upon the outside of the shaft 96. This oil groove 126 carries the oil upwardly to the space between the bearings 86 and 88 and a second oil groove 128 is provided for carrying the oil up to the bearing 88.

20 The cylinder block 106 is provided with a low pressure suction inlet 130 extending radially inwardly next to the divider block 132 which is provided within a slot in the wall of the cylinder block 106. The divider block 132 is kept pressed against the outer surface of the impeller member 104 by a two-compression type coil spring 134 which is anchored at the outer end by a bracket 138 fastened by the cap-screw threaded into the member 78. The electric motor operates to rotate the shaft 96 and the impeller 104 in a clockwise direction as viewed in Figs. 3, 4 and 5.

Operation of first form of compressor

Fig. 4 shows the initial portion of a suction stroke when the gas from the low pressure suction inlet 130 is beginning to be drawn into the space designated by the reference character 140 located between the divider block, the portion of the cylinder wall around the low pressure suction inlet 130 and the adjacent wall of the impeller member 104. As the impeller moves further in a clockwise direction, this space grows in size until it includes the entire space between the impeller member 104 and the cylinder block 106 as shown in Fig. 5. It will be seen that in Fig. 5 the inlet port is almost covered by the impeller member 104. This position therefore shows that a full charge of gas has been drawn into the compressor and that further movement to the position shown in Fig. 3 will cause the closing of the suction inlet port 130 and the beginning of compression.

In order to use this same compressor for pumping the gas from the separator, the high pressure suction line 50 is connected to a fitting 144 which is threaded into the side of the cylinder block almost opposite the low pressure inlet port 130. This threaded fitting 144 leads to a downwardly extending passage 146 in the cylinder block 106 and this passage 146 connects with a passage 148 extending generally radially inwardly and connecting with a short upwardly extending passage 150. This upwardly extending passage 150 ends up in a port provided in the upper surface of the bottom plate 112 upon which the impeller member 104 rests. This port 150 is so located that it is at all times within the confines of the impeller member 104. The impeller member 104, however, is provided with a slot 152 in the form of an arc which is adapted to register with the port 150. The bottom plate 112 is provided with a depression 154 which has about one-third of its width uncovered when the impeller member 104 is in the position shown in Fig. 3. The remaining portion is covered at all times by the impeller

member 104, but a portion thereof will register with the slot 152 between the positions of the impeller shown in Figs. 4 and 5.

It will be seen that when the impeller is in the position shown in Fig. 5 in which the low pressure in port 130 is not fully covered, the slot 152 is not in registration with either the port 150 or the depression 154. A portion of the depression 154 is uncovered but is not connected either with the slot 152 or port 150 in any way whatsoever. However, as soon as the impeller moves a few degrees further in a clockwise direction the slot 152 begins to extend over a portion of the depression 154. This, however, merely allows communication between the slot 152 and the compression chamber which is, of course, located between the impeller 104 and the cylinder block 106. However, as soon as the slot 152 reaches the nearest or entering edge of the port 150 the high pressure gas from the separator 36 then can pass through the conduit 50, the threaded fitting 144, the down passage 146, the radial passage 148 to the port passage 150, thence through the slot 152 to the depression 154 and thence into the compression chamber. This high pressure gas readily flows into the compression chamber since the compression chamber has been filled only with a low pressure gas from the evaporator and substantially no compression thereof has taken place. This gas then flows into the compression space until the pressure within the compression space substantially equals the pressure in the high pressure suction conduit 50.

The gas from the suction conduit 50 is permitted to flow into the compression chamber until the trailing edge of the slot 152 is no longer in registration with the depression 154. In Fig. 4 the trailing edge of the slot 152 is shown leaving the depression 154. It will be seen that the depression 154 has been almost covered by the impeller member 104 and that further rotation will cover the depression 154 in increasing amounts so that within less than one-eighth of a revolution the depression 154 will be completely covered and further compression will take place entirely within the compression chamber since the compression chamber for the remainder of the compression stroke no longer has access to the depression 154, the slot 152 or the port 150.

From this point on the compression stroke, the impeller must merely raise the pressure of the refrigerant within the compression chamber to condenser pressure and then expel this gas from the compression chamber through the outlet port 156 located in the bottom plate 112 adjacent the divider block 132. The outlet port 156 is provided with a check valve 158 which allows the compressed gas to flow into the muffler 118 but prevents any gas from flowing from the muffler 118 back to the outlet port 156. The muffler 118 includes a series of chambers designated by the reference character 160 which are connected by small apertures 162 located in the dividing wall between each of the chambers excepting one wall of the chamber which contains the discharge check valve 158.

The particular chamber connected upon the opposite side of the wall having no aperture 162 is provided with an outlet in the form of a passage 164 which extends upwardly through the bottom plate 112, the cylinder block 106 and the frame member 78 and opens into the interior of the sealed unit above the oil level. This compressed gas is then removed from the sealed unit 75

through the conduit 166 which connects the sealed unit 30 with the condenser 32.

Second form of compressor

In Figs. 13 to 17 there is shown a modified form of the compressor in which a port in the casing feeds the high pressure gas directly to a port in the impeller which discharges directly through the periphery of the impeller into the compression chamber. In this form there is provided a cylinder block 200 containing a slot receiving a divider block 202 pressed inwardly by the compression spring 204 which presses the divider block against an eccentric type impeller 206, which is keyed to a drive shaft. Beneath the cylinder block 200 is a bottom plate 208 and a muffler 210. The low pressure gas enters the compression chamber through the low pressure suction port 212 located upon one side of the divider block 202 and the compressed gas is discharged through the outlet port 214 located upon the opposite side of the divider block in the bottom plate. This discharge outlet 214 is provided with a check valve and feeds into the muffler and thence into the interior of the sealed unit in a like manner as is illustrated in Figs. 2 to 12. A passage 216 is provided for feeding the compressed gas from the muffler to the interior of the sealed unit casing.

Operation of second form of compressor

The suction stroke of the compressor begins with the position of the impeller shown in Fig. 16. As the impeller continues to turn in a clockwise direction there is a space which develops between the cylinder block 200, the divider block 202 and the adjacent portion of the impeller 206. This chamber gradually grows in size by the further clockwise rotation of the impeller 206 until it takes in the entire space between the impeller 206 and the cylinder block 200 as shown in Fig. 13. Further clockwise movement to the position shown in Fig. 14 causes the impeller to close the low pressure suction inlet port 212 and begins the compression stroke.

The cylinder block as shown in Fig. 17 is provided with a threaded high pressure inlet connection 218 which is provided for connection with a threaded fitting like that designated by the reference character 144 in Fig. 5. The threaded connection 218 connects to a downwardly extending passage 220 which at its lower end connects to the laterally extending passage 222 in the bottom plate 208. This laterally extending passage ends in the port 224 in the upper surface of the bottom plate 208. The impeller 206 is provided with a port 226 adapted to register with the port 224 in the bottom plate at a certain portion of each revolution of the impeller and this port 226 communicates directly with the compression chamber. When the impeller 206 is in the position shown in Fig. 14 the ports 226 and 224 are not in registration but the low pressure suction inlet port has just been closed and the leading edge of the port 226 is just at the point of extending over one edge of the port 224 and any further movement will permit gas to flow from the passages 220 and 222 into the port 226 and from there into the compression chamber.

Further movement in a clockwise direction to the position shown in Fig. 15 will cause the port 226 to move into complete registration with the port 224 thus permitting the free flow of gas from the high pressure suction line into the compression chamber. Previous to the uncovering of the

high pressure suction port 224 the compression chamber has been filled with low pressure gas from the low pressure suction inlet 212. Very little compression has taken place when the impeller moves to the position shown in Fig. 15. When the impeller does move to the position shown in Fig. 15 the high pressure gas may flow freely into the compression chamber and compress the low pressure gas and raise the pressure in the compressing chamber substantially to the pressure found in the high pressure suction.

Fig. 16 shows the trailing edge of port 226 at the point of leaving the edge of the port 224 thus closing the compression chamber to the admission of the high pressure suction gas. The remainder of the compression stroke consists in compressing this gas in a compression chamber and forcing the compressed gas through the outlet port 214. This compression stroke is completed when the eccentric reaches the position shown in Fig. 13. This modification therefore is a simplified form of the compressor as shown in Figs. 2 to 12.

It has been found that in large compressors the rubbing velocities between the eccentric, the bottom plate, the cylinder block and the upper surface of the compression chamber are relatively high; and even though good lubrication is provided, this high rubbing velocity entails a considerable drag upon the impeller so that the no-load power consumption is relatively high. In order to overcome this relatively high no-load power consumption I have provided in Figs. 18 to 24 two forms of compressors in which there is employed a roller type impeller comprising a roller rotatably mounted upon an eccentric driving member.

Third form of compressor

Referring now to the form shown in Figs. 18 to 20 there is provided a cylinder block 302 which is slotted to receive a divider block 304 pressed inwardly by a compression spring 306 into engagement with the periphery of a roller 308 which is rotatably mounted upon an eccentric 310 formed upon the lower end of a drive shaft 312. A low pressure suction inlet port 314 is provided for admitting low pressure suction gas into the compression chamber while on the opposite side of the divider block the discharge outlet port 316 is provided. This outlet port discharges through a check valve (not shown) into a muffler 318 provided beneath the bottom plate 320 of the compressor proper.

The cylinder block 302 is provided with a threaded opening 322 for receiving the threaded connection of the high pressure suction conduit such as a fitting like the threaded fitting 144 shown in Fig. 5. This threaded opening 322 connects with the downwardly extending passage 324 which at its lower end connects with the laterally extending passage 326 in the bottom plate 320. This bottom plate 320 is provided with a high pressure suction port 328 which is adapted to be covered by the roller 308 except when the roller is between the positions shown in Figs. 18 and 19. This high pressure suction port begins to uncover when the eccentric and roller impeller moves in a clockwise direction from the position shown in Fig. 18. The port 328 is shown at the point of being uncovered in Fig. 18.

It will be seen at this time that the gas entering the compression chamber through the port 328 at this time can flow through the compression chamber until it reaches the low pressure suction inlet port 314, since at this time the

roller has not progressed far enough to cover the suction inlet port 314 or to keep the two inlet ports separated. Therefore I have provided a shoulder at the suction inlet port which supports a light compression spring 330 exerting force against the check valve 332 which seats upon a seat 334 of a rubber-like material such as polymerized chloro-2-butadiene 1,3, commonly called chloroprene rubber. This rubber-like seat 334 is supported by a plug 336 which also serves as a connection fitting for the low pressure suction line. The check valve 332 is provided with prongs at its edge so as to prevent it from seating upon the second shoulder which is provided for limiting the opening of the check valve.

As the roller 308 moves from the position shown in Fig. 18 in a clockwise direction to the position shown in Fig. 19, the port 328 is fully opened and again substantially closed as shown in Fig. 19. During this movement some compression is taking place and in order to prevent the compressing charge of low pressure suction gas and the high pressure suction gas from escaping from the compression chamber through the high pressure suction port 328, I have provided a check valve 338 directly beneath the high pressure suction port 328. This check valve is provided with a seat of chloroprene rubber 340 in an insert or plug 342 in the bottom plate 320. By the use of these two check valves, gas once entering the compression chamber is prevented from leaving the compression chamber except through the outlet port 316.

Fourth form of compressor

In Figs. 21 to 24 I have shown an improved form in which the high pressure suction inlet port is so located that no check valves are required although a check valve similar to the construction shown in Fig. 20 may be used for the high pressure suction inlet, if desired. In this form there is provided a cylinder block 402 which is slotted to receive the divider block 404 pressed inwardly by a light compression spring 406 into engagement with the periphery of a roller 408 which is rotatably mounted upon eccentric 410 provided at the lower end of a drive shaft 412. The remainder of the compressor and sealed unit may be like that shown in Figs. 2 to 12. A suction inlet port 414 is provided in the cylinder block 402 adjacent the divider block 404 and upon the opposite side of the divider block there is provided an outlet port 416 preferably provided with a check valve for controlling the discharge of compressed gas into the muffler 418 located below the bottom plate 420 of the compressor casing. The compressed gas discharged into the muffler 418 is discharged into the casing of the sealed unit through an upwardly extending passage 422 in the cylinder block 402 and in the bearing frame of the compressor.

Operation of fourth form of compressor

The suction stroke of the compressor begins with the roller impeller 408 in the position shown in Fig. 21 and further movement provides a space bounded by the divider block, the cylinder block and the portion of the periphery of the impeller adjacent the low pressure suction inlet port 414. Further clockwise movement of the roller impeller 408 enlarges this space as is shown by the movement to the position shown in Fig. 22. This suction stroke is completed when the roller impeller 408 makes the complete

revolution and returns to the position shown in Fig. 21.

The cylinder block 402 is provided with a threaded opening 424 for receiving a threaded fitting like that designated by the reference character 144 for connection with the high pressure suction conduit. The threaded opening 424 at its inner end connects with the downwardly extending passage 426 connecting at its lower end with its laterally extending passage 428 in the bottom plate 420. A curved port 430 is provided between about 245° and 280° from the divider block in the direction of rotation in the upper surface of the bottom plate 420 connecting with the laterally extending passage 428. This curved high pressure suction inlet port 430 is so located that it is just at the point of being uncovered when the roller impeller is at the position shown in Fig. 21. Further clockwise movement of the roller impeller 408 to the position shown in Fig. 23 fully uncovers the curved high pressure suction inlet port 430 as shown in Fig. 23. The suction and compression strokes together make a complete cycle requiring two revolutions for its completion. However, the compression stroke of one cycle and the suction stroke of the succeeding cycle take place simultaneously to allow a discharge each revolution. This permits the high pressure suction gas to enter the compression chamber and press the low pressure suction gas to the pressure of the high pressure suction gas and to substantially completely fill the portion of the compression chamber in communication with this port at this time. Further clockwise movement of the roller impeller to the position shown in Fig. 22 will again completely cover the high pressure inlet port 430 and permit the remainder of the compression stroke to proceed in the customary manner so that the gas is brought to compression pressure and expelled through the outlet port 416.

If desired this high pressure suction inlet port 430 may be provided with a check valve like that provided for the high pressure suction inlet port 328 but no check valve is required for the low pressure suction port 414 and none is necessary for the high pressure suction port. In this form it is desirable that the low pressure suction port be placed as close as possible to the divider block 404 and it is also desirable that the eccentric 410 have as much eccentricity as is possible consistent with other conditions. This greater amount of eccentricity is desirable in order to provide more rapid movement and a larger port

opening for high pressure suction inlet in order to decrease the amount of rotation during which the high pressure suction inlet port is uncovered.

5 Thus I have provided an improved form of refrigerating system with an improved form of multiple effect rotary compressor shown in four different variations. In all these forms a relatively simple efficient multiple effect rotary compressor is provided. For certain forms a novel 10 type of oiling system is provided. It is not necessary that these compressors be used with the particular form of system shown in Fig. 1, but the compressor may be used wherever it is desired 15 to compress gas from two different suction pressures to discharge pressure and in an efficient manner.

While the form of embodiment of the invention as herein disclosed, constitutes a preferred 20 form, it is to be understood that other forms might be adopted, all coming within the scope of the claim which follows.

What is claimed is as follows:

A multiple effect rotary compressor for drawing gas through high and low pressure gas inlets, including an impeller casing provided with spaced parallel plane wall surfaces and a round wall surface extending between the plane wall surfaces, an impeller having surfaces in sealing 25 relation with the spaced walls of the casing, said impeller being provided with a round surface between the parallel surfaces different in diameter than the round surface of the casing to provide a pumping chamber between the impeller 30 and the casing, means for providing a seal transversely across the pumping chamber between one portion of the casing and the impeller to provide a division in the pumping chamber, a low pressure gas inlet and an outlet communicating with 35 the pumping chamber upon opposite sides of said seal, means for moving the round wall surface of the impeller progressively into sealing relation with successive portions of the round wall surfaces of the casing beginning with the low pressure 40 gas inlet and ending with said outlet, a high pressure gas inlet port so located entirely in one of said plane wall surfaces remote from the round wall surface of said casing that it is entirely 45 separated and sealed from the low pressure inlet by the impeller during the initial portion of each cycle and uncovered during an intermediate portion of each cycle and separated and sealed from the outlet by the impeller during 50 the final portion of each cycle.
